(57) **CLAIM**

The ornamental design for portions of a connector plug and receptacle pair, as shown and described.

DESCRIPTION

FIG. 1 is a front elevation view of a connector plug showing our new design;

FIG. 2 is a perspective view thereof;

FIG. 3 is a front elevation view of a connector receptacle showing our new design;

FIG. 4 is a perspective thereof; and,

FIG. 5 is a front elevation view of portions of a connector plug and receptacle pair, shown in a common stowage.

The broken line showing of the remainder of the connector plug and the connector receptacle, and the common stowage is for illustrative purposes only and forms no part of the claimed design.

1 Claim, 3 Drawing Sheets
